UNITED STATES PATENT OFFICE.

GEORGE L. KNAUSS, OF ALLENTOWN, ASSIGNOR TO THE HYATT SCHOOL SLATE COMPANY, (LIMITED,) OF BETHLEHEM, PENNSYLVANIA.

SANDPAPERING-MACHINE.

SPECIFICATION forming part of Letters Patent No. 366,009, dated July 5, 1887.

Application filed June 24, 1886. Serial No. 206,100. (No model.)

To all whom it may concern:

Be it known that I, GEORGE L. KNAUSS, a citizen of the United States, residing at the city of Allentown, in the county of Lehigh, 5 State of Pennsylvania, have invented certain new and useful Improvements in Sandpapering-Machines, of which the following is a specification, reference being had therein to the accompanying drawings.

This invention has relation to sandpapering-machines adapted by certain features of construction to smoothing opposite sides of slate-frames after the same have been applied to slates, the object of the invention being to provide means which shall automatically feed a series of succeeding slates to smoothing mechanism which finishes one side of each frame, which is afterward reversed by hand and submitted to a similar mechanism for the finishing of the opposite side, when each slate is subsequently and automatically passed through and between cleaning and polishing mechanism.

Other subsidiary objects of the invention 25 and its various advantages will appear in the following description, and the novel features thereof will be particularly pointed out in the claims.

Referring to the drawings, Figure 1 is a plan, 30 and Fig. 2 a side elevation, (parts being broken away on transverse lines to economize space in the drawings.) Fig. 3 is a central vertical section through the feeding and smoothing mechanisms at one end of the machine; and Fig. 4 is a side elevation, on an enlarged scale, of the pressure-rolls and adjacent parts.

Like letters of reference indicate like parts in all the figures of the drawings.

40 A represents the frame-work upon which the several elements of the machine are mounted, said frame-work being continuous and unbroken, although represented in the drawings as broken on a vertical transverse line and as having a portion of one end removed for the purpose of permitting the illustration of the parts on a larger scale than would be possible if shown complete.

Upon the frame-work or table A are stands A', which serve as supports for the several devices arranged on the frame-work.

A² represents a table or plate having guides A³ A⁴ thereon, the latter being adjustable by means of binding-bolts and nuts A⁵, which pass through slots A⁶, formed in the bed. A single 55 bolt and nut, A⁵, in the guide A³, permits of said guide being swung upon its bolt away from the smoothing disk, as hereinafter described.

B B represent feed-rolls, which may be of any usual construction, but which in this instance comprise a core, B', (see Fig. 3,) surrounded by a coil, B², of rope or other flexible material. As usual in feed-rolls of this class the covering B² may be made of rubber in the form of a tube slipped upon the core. The lower feed-roll, B, or, rather, the boxes B³ in which the journals of said rolls revolve, are supported in suitable ways formed in the standard A' upon a bolt, B⁴, threaded in the frame-work and having a set-nut, B⁵, whereby the said lower roll may be elevated or depressed to adjust its upper surface in the same horizontal plane as that of the bed A². The upper roll, B, runs in similar boxes, which are supported by a hollow tube, B⁶, (secured on the standard A',) having therein a coiled spring, (not shown,) and provided at its upper end with an adjusting-belt, B⁷, and set-nut B⁸, whereby the upper roll, B, may be adjusted to press 75 upon the lower roll yieldingly. As shown, the two feed-rolls are geared to each other, so that motion given to one will be communicated to the other.

The smoothing-disk C is mounted upon a 85 vertical shaft, C', at the lower end of which is a bearing or journal-box, C², secured in any suitable manner to the frame-work A, and having in line with the shaft the adjusting-bolt C³, provided with a set-nut, C⁴, whereby 90 said shaft and smoothing-disk may be adjusted vertically to lie in a common plane with the bed A² of the machine.

On the shaft C' of the smoothing-disk is a flanged pulley, D, which serves the purpose 95 of connecting the two smoothing-disk shafts C' of the complete machine together by a belt, whereby uniformity of motion is given both disks.

It will be seen by reference to the drawings that the complete machine comprises 100 two separate smoothing and feeding mechan-

isms, each of which is exactly like the other in detail, except as to the specific method of communicating motion from one to the other, as received from a main counter-shaft, hereinafter described.

So far as the details are similar, similar letters of reference are used, and the description of one of said mechanisms is fully applicable to the other.

Upon the vertical shaft C' of the first smoothing-disk is a second flanged pulley, E, which receives motion from a pulley, E', on the main counter-shaft F, which is provided with fast and loose pulleys F', which receive the belt from the motor. The shaft of the lower feed-roll, B, of the first smoothing mechanism is provided with two belt-pulleys, G G', the latter of which is connected by a belt with the pulley G' of the second smoothing mechanism, whereby uniform motion is given to the feed-rolls of both mechanisms. A pulley, H, on the main counter-shaft F, is belted to a pulley, H', on a shaft, H'', supported beneath the bed of the machine by hangers H'', and on the shaft H'', beneath the machine, are mounted two pulleys, H' and H'', the latter being connected by a belt with the pulley G on the shaft of the lower feed-roll, B, whereby motion is imparted from the counter-shaft pulley H to the feed-rolls of both machines, the several pulleys being proportioned in size to give the required speed of rotation of each of the moving parts operated.

Beyond the second smoothing mechanism there is mounted upon the bed a pair of revolving cleaning and polishing brushes, I, the bearing-boxes I' of which are adjustably secured in the standard A' by means of a T-slot formed therein and a T-rib, I'', on the back of each bearing-box, a bolt, I'', serving to maintain each box in an adjusted position. Upon the end of the shaft of each of the brushes I is a belt-pulley, I', whereby each of the brushes may be connected to the pulley J, mounted on the counter-shaft J' in hangers J'', depending from the frame-work. Upon the same shaft is a pulley, K, which, by a suitable belt, is connected with a pulley, K', on the main counter-shaft, whereby (said pulley K' being smaller than the pulley H) a higher speed of rotation is given the brushes than to the feed-rolls of the machine, whereby not only do the brushes remove the dust made in the smoothing operation, but they also act to polish the smoothed frames as they pass through and between said brushes.

In the drawings, wherever the location of the connecting-belts can be shown without rendering the illustrations confused said belts are shown by dotted lines.

The smoothing mechanism comprises a disk, L, preferably of metal, having a central hub, L, which is mounted upon the vertical shaft C'. Upon the metal disk is mounted the smoothing-disk proper, C, upon which is secured, by means of a band, C'', a covering, C', of sand-paper or other abrading material.

Screws C' serve to retain the band and abrading material in position.

M M represent yielding pressure-rolls arranged above the smoothing-disk, for the purpose of holding the slate-frames in contact therewith. Each of the rolls M is mounted in bearings N, which are formed at the ends of the arms N', which are pivoted in blocks N'', secured to the bed A'', whereby each of said rolls may be swung upwardly over and away from the disk, so that when the guide A''' is swung therefrom, as heretofore described, free access is had to the disk for the purpose of applying new abrading material thereto. The pressure-rolls are yieldingly held by means of a coiled spring, O, arranged about an eyebolt, O', provided with set-nuts O'', which bolt projects through a T-block, O'', and is pivoted in the base-block O', secured to the bed A'' of the machine, between the two rolls. Projections N''' on the arms N'' rest beneath the lateral projections O''' of the T-block O'', which block is perforated so as to move up and down on the eyebolt O', said movement being permitted by the spring O, arranged on said bolt. When it is desired to raise the rolls M and throw them away from over the disk, the set-nuts O'' on the bolt O' are loosened, or the T-block is forced upward, and said bolt is thrown sideways on its pivot, so that the projections O''' of the T-block are moved away from over the projections N''' of the arms N''. The adjusting-bolts N'' in said arm serve to limit the downward movement of the rolls, and therefore determining their pressure upon the slates passing thereunder and over and along the smoothing-disk.

This being the construction, the operation is as follows: One person introduces slates one after another at that end of the machine at which the main counter-shaft is arranged, and the slates passing through and between the feed-rolls B serve to push the preceding slates along in the guides and over the first smoothing-disk C and beneath the pressure-rolls M, where, by the rotation of the smoothing-disk, one side of the frame is smoothed. As each slate passes out of the first machine, it is by a second person reversed and introduced into the guides of the second machine with the smoothed side upward, so that by means of the feed-rolls its unsmoothed side is presented to the second smoothing-disk C for a repetition of the operation performed by the first, after which the slate is automatically passed through between the cleaning and polishing rotating brushes I, from which it emerges smoothed and polished.

The pressure-rolls M may be of the same construction as that of the feed-rolls; but in view of the fact that the smoothed side of the slate-frame comes in contact therewith it is preferable to employ pressure-rolls having a covering of rubber or other non-abrading material.

Having described the invention and its operation, what is claimed is—

1. The combination, with the counter-shaft F, provided with the pulleys E' H K', of the frame A, provided with counter-shafts H² J' and with the independent smoothing and feeding mechanisms mounted on separate beds, and the final cleaning and polishing mechanism I, substantially as specified.

2. The combination of the smoothing-disk C, pressure-rolls pivotally and yieldingly supported above said disk, the bed A², and the guide-strips pivotally and adjustably secured to the bed, substantially as specified.

3. The combination of the rolls M, arms N', having bearings N, and blocks N², with the adjusting-bolts N⁴ and bed A², substantially as specified.

4. The combination of the arms N', having projections N³, blocks N², T-block O³, eyebolt

O', spring O, and set-nuts O², substantially as specified.

5. The combination of the frame A, the separate beds A², mounted upon standards A', the feed-rolls B, the adjusting-bolt B⁴ B⁷, the smoothing-disk C, the vertical shaft C', having the adjustable bearing C² and the flanged pulleys D E, the second disk-shaft provided with the single flanged pulley D, and the counter-shaft H² J', having the pulleys J K, and the smoothing-rolls I, having the pulleys I⁴, substantially as specified.

In testimony whereof I affix my signature in presence of two witnesses.

GEORGE L. KNAUSS.
